UNITED STATES PATENT OFFICE

2,597,419

HYDRAULIC SERVOMOTOR AND THE LIKE

Roy Westbury, Bridgnorth, and Stanley Ralph Tyler, Willenhall, England, assignors to H. M. Hobson Limited, London, England, a company of Great Britain

Application May 27, 1950, Serial No. 164,655
In Great Britain June 2, 1949

6 Claims. (Cl. 60—97)

1

This invention relates to systems for the hydraulic control of an output member of the kind comprising a hydraulic actuator (i. e. a jack or motor) controlled by a control valve, operable by a manually operated input member to establish alternative pressure and exhaust connections to the actuator to cause the output member to move in a direction and to an extent determined by the movement imparted to the input member.

As a safety measure against failure of the pressure supply, or leakage in the system, it would be possible to duplicate the system and to provide two actuators in tandem or in parallel, both operating on the output member and each having a separate control valve and deriving pressure liquid from a separate pressure supply, the two control valves being operated by a common input member. Mere duplication, however, does not guard against the results arising from seizure of one of the control valves. This may cause disastrous results in the case of operation of control surfaces of aircraft, as if the valve seizes in an open position the pressure liquid may drive the control surface to an undesired extreme position.

With a view to avoiding this disadvantage, the invention provides a hydraulic system of the above kind comprising a collapsible member linked to the input member and adapted to collapse when subjected to a predetermined load as the result of valve seizure and consequent excessive application of manual force to the input member, and a valve, arranged to be operated by collapse of the collapsible member to short circuit the actuator by establishing direct liquid communication between opposite sides thereof.

Consequently, if the control valve seizes and the collapsible member is collapsed by reason of the application of increased force to the input member, the output member may be operated by another actuator deriving pressure from an alternative supply.

Preferably the valve actuated by collapse of the collapsible member is also arranged to cut off the pressure supply to the control valve.

Two embodiments of the invention will now be described in detail, by way of example, with reference to the accompanying drawings, in which:

Fig. 1 is a diagrammatic showing of a hydraulic jack according to the invention,

Fig. 2 is a diagram showing the application of the invention to a system embodying two hydraulic jacks in tandem, and

2

Figs. 3 and 3a are diagrams showing the application of the invention to a system embodying two hydraulic motors.

Like reference numerals indicate like parts throughout the figures.

Considering Fig. 1, first of all, the installation shown therein includes a hydraulic jack 10, the piston 11 of which carries a piston rod 12, which projects from the jack cylinder 13 and is provided at 14 to a fixed point 15 of the aircraft structure. Inside the piston rod is a pressurising piston 16 loaded by a spring 17, the piston 16 serving to apply pressure, through a hole 18 in the piston rod 12, to the liquid contained in the cylinder 13.

The cylinder 13 is pivoted, at 19, to an output member 20 for applying movement, as the cylinder 13 moves in relation to the jack piston 11, to an aileron or other control surface 21. The object of the pressurising piston 16 is to maintain maximum rigidity of the liquid in the connection between the control surface 21 and the aircraft, for the purpose of preventing flutter of the control surface.

Fixed to the cylinder 13 are:

- (a) The housing 22 of a collapsible member 23,
- (b) A pair of stops 24,
- (c) A control valve housing 25,
- (d) The housing 26 of a pair of non-return valves,

(e) The housing 27 of a supply check valve and a jack by-pass valve, and

- (f) The housing 28 of a return check valve.

Fig. 1 being purely diagrammatic, the connections between the cylinder 13 and the parts 22 and 24—28 are not shown therein.

An input member 29, connected to the pilot's control column, carries a projection 30 which moves with clearance between the stops 24 during normal operation of the jack. The input member 29 is pivoted at 31 to a link 32 pivoted at one end, 33, to the collapsible member 23 and at the other end, 34, to a link 35 for imparting movement to the control valve 36 of the jack.

Liquid under pressure, supplied through an inlet 37, normally holds a tubular non-return valve 38 open, against a spring 39, and so obtains access to a line 40 controlled by the middle land of the control valve 36. The hydraulic pressure also urges to the right, against a spring 42, a piston 43, thereby holding a non-return valve 44 open against its spring 45. This places in communication with an exhaust outlet 46 lines 47 controlled by the outer lands of the control valve 36.

During normal operation of the jack, the link

32 will, on movement of the input member 29, pivot about the point 33 and displace the control valve 36 to connect, in conventional fashion, through lines 48, 49 one end of the cylinder 13 to pressure and the other to exhaust. The cylinder 13 will then move, in the same direction as the control valve 36, until the housing 25, which travels with it, causes the lands of the control valve again to mask the ports in the housing communicating with the lines 40, 47. The cylinder 13 thus moves to an extent and in a direction determined by the movement of the input member 29.

In the event of failure of the hydraulic pressure, the non-return valves 38, 44 close to trap liquid in the jack. Manual operation of the jack is then possible by moving the input member 29 sufficiently for it to actuate one or other of the stops 24 to move the jack cylinder 13. When the input member 29 is so moved, the central land of the control valve 36 opens a port 50 to allow, as described in U. S. application 785,837, now Patent No. 2,566,273, dated August 28, 1951, trapped liquid to circulate from one end of the cylinder to the other through one or other of a pair of non-return valves 151.

The collapsible member 23, which is described in detail in U. S. application Serial No. 164,653 serves to deal with the contingency of the control valve 36 seizing in its housing 25 during normal hydraulic operation of the jack. It comprises a cylindrical tube 51, which is a close fit in a cavity in the housing 22 and free to slide therein, a plunger 52 slideable in the tube 51, a plurality of balls 53, and a compression spring 54. The tube 51 is pivoted at 33 to the link 32 and the spring 54 is mounted in compression between the head of the plunger 52 and the end of the tube 51. The balls 53 project through holes 55 in the tube 51 and into holes 56 in the housing 22 and normally the outer and smaller portion of each ball 53 projects into and fits closely within the holes 55, 56. The plunger 52 has an inwardly tapering head 57 which presses the balls 53 outwards into the position illustrated.

The balls 53 consequently resist sliding movement of the tube 51 in relation to the housing 22, as such movement would necessitate that the balls ride inwardly down the tapered face of the head 57 and consequently in movement of the plunger 52 to the right, thereby increasing the compression of the spring 54. When, however, the load seeking to move the tube 51 axially in relation to the housing 22, and imposed thereon by the pilot in the effort to free the control valve 36, when seized, reaches a predetermined limit, the balls 53 will be moved inwardly to an extent sufficient for them to cease resisting movement of the tube 51, with the result that the member 23 is collapsed.

A resetting plug 58, having a conical head 59, may be moved into the tube 51, to reset the member 23. After the tube 51 has been moved back into position to align the holes 55 with the holes 56, pressure on the plug 58 will force the balls 53 back into the position shown.

Mounted within the tubular non-return valve 38 is a closely fitting plunger 60. This plunger is normally held down by a leaf spring 61, one end of which is attached to a member 62 pivoted at 63 to the housing 27, and the other end of which carries a catch 64 engaging a corresponding catch 65 on the tube 51. The lower end of the spring-loaded plunger 60 extends into an annular chamber 66 communicating with one end

5 of the cylinder 13, while the other end of the cylinder communicates with a port 67 in the annular chamber 66 which is normally sealed by the end of the spring-loaded plunger 60. The area of the port 67 is equal to half the cross-sectional area of the portion of the plunger stem enclosed in the annular chamber 66, so that the plunger 60 is subjected to equal upward loads by a given pressure existing in either end of the cylinder.

10 A subsidiary function of the spring-loaded plunger 60 is to prevent excessive pressure being generated at either end of the cylinder 13 due to excessive reaction load from the control surface 21. The leaf spring 61 is so designed that the plunger 60 may lift against it, under excessive pressure on its lower end, or on the differential area thereof exposed to the pressure in the chamber 66, thereby relieving the pressure in the cylinder. The plunger 60 will of course move down again to sealing position when the reaction load has returned to a safe value.

15 The main function of the spring-loaded plunger is however fulfilled when the collapsible member 23 collapses due to seizure of the control valve 36. The catch 65 is then removed from the catch 64 on the leaf spring 61, which is thus disabled whereupon the plunger 60 is lifted by the hydraulic pressure acting on its lower end, affording free communication between the two ends of the cylinder 13. As the plunger 60 lifts, a collar 68 on it closes the non-return valve 38 and cuts off the pressure supply to the control valve 36.

20 As communication is opened between the two ends of the cylinder 13 when the collapsible member 23 collapses, the system offers no resistance to movement of the control surface 21 by a second hydraulic system, which may be constituted by an exactly similar hydraulic jack, deriving pressure from a different source, and the control valve of which is also linked to the pilot's input member 29.

25 In the case of the installation shown in Fig. 2, two jack pistons 11, 11a are mounted in tandem on a common piston rod 12, pivoted at 14 to the aircraft structure and movable respectively in cylinders 13, 13a in a common housing 113 which constitutes an output member connected to a control surface or to the head of the rotor of a helicopter. Movement of the housing 113 thus serves to impart movement to the control surface or to adjust the rotor head, e. g. by varying the blade pitch or by tilting the rotor head.

30 Parts associated with the jack piston 11 bear the same reference as the corresponding parts in Fig. 1, while parts associated with the jack piston 11a bear the same reference numerals as the corresponding parts associated with the jack piston 11, but with the addition of the suffix *a*.

35 The pilot's input member 29 is connected to a member 69, pivoted at 70 and having a nose 71 which is movable between the stops 24. The member 69 is connected, by links 72, 72a to links 32, 32a.

40 Normally, movement of the input member 29 will rock the links 32, 32a in opposite directions about their points 33, 33a of pivotal attachment to their respective collapsible members 23, 23a to move the control valves 36, 36a in the same direction, thereby admitting hydraulic fluid to the corresponding ends of the two cylinders 13, 13a and establishing exhaust connections to the opposite ends of the jack cylinders.

45 If, however, one of the control valves, say the

control valve 36, seizes, the force exerted by a pilot on the input member 29 will collapse the associated collapsible member 23. The associated valve 60 will then move, precisely as described with reference to Fig. 1, to cut off the pressure supply from the associated control valve 36 and to establish a by-pass connection between opposite ends of the jack cylinder 13. The failed jack then offers no resistance to continued operation of the output member by the other jack, which is controlled by its control valve 36a. After the member 23 has collapsed, the link 32 turns idly, in response to movement of the input member, 29, about its point of attachment 34 to the seized control valve 36. Stops (not shown) serve to limit the movement of the valve 36.

In the arrangement shown in Figs. 3 and 3a, two hydraulic motors 83, 83a serve to operate a control surface. Parts associated with these motors which correspond to parts shown in Fig. 1 bear the same reference numerals. Also parts associated with the motor 83a which correspond to parts associated with the motor 83 bear the same reference numerals, with the addition of the suffix *a*.

The pilot's input member 29 is connected to a link 84 which, on movement of the input member, turns about a pivot 85 to shift a linkage 86, 87, 87a, 187, 187a, thereby moving the two control valves 36, 36a in the same direction.

But one of the hydraulic motors, 83, will be described, the other 83a, being of precisely similar construction. The motor 83 comprises a shaft 88, carrying a pair of eccentrics 89, 90 spaced at 180° (i. e. in antiphase) on the shaft. Associated with the eccentric 89 is a set of six cylinders, each containing a piston 91, these cylinders being located radially in relation to the shaft 88. A similar set of six cylinders each containing a piston 92, is associated with the eccentric 90. Associated with each aligned pair of cylinders is one of six distributing valves 93, each of which is held by a spring 94 in contact with a swashplate 95 on the shaft 88. For simplicity but one pair of aligned cylinders, containing pistons 91, 92, and but one associated distributing valve 93, are shown in Fig. 3a. The motor has a drain connection 183 for leading away liquid which may leak past the pistons 91, 92 or the distributing valves 93.

On displacement of the control valve 36, it establishes alternative pressure and exhaust connections to lines 96, 97 leading to each of the distributing valves 93. This results in sympathetic movement of the pistons 91, 92 thereby actuating the eccentrics 89, 90 to rotate the shaft 88 in a direction determined by the direction of movement of the control valve 36. Thus, if line 96 is connected to pressure, and line 97 to exhaust, the piston 92 will be caused to move in and the piston 91 to move out. As the shaft 88 rotates, the swash plate 95 imparts continuous reciprocating movement to all of the valves 93 so that the associated pistons 91, 92 will be alternately connected, at the proper times, to pressure and exhaust.

The shafts 88, 88a of the two motors drive, through gear wheels 98, 98a a common gear wheel 99 connected, by bevel gearing 100, to a threaded sleeve 101, engaging a pair of screw jacks 102 which are moved inwards or outwards, according to the direction of rotation of the member 101, to impart movement to the two portions of the control surface, not shown.

In screw threaded engagement with the boss

of the gear wheel 99 is a follow-up rod 103 which operates, by rocking the link 84 about its pivotal attachment 104 to the input member 29, to return the control valves 36, 36a to neutral position.

If either of the control valves, say 36, should seize, the following sequence of events occurs. The associated collapsible member 23 collapses, thereby freeing the catch 77 associated with the corresponding valve 160, which closes under the action of its spring 78. This cuts off pressure from the control valve 36, and also from a line 105. As long as there is pressure in the line 105, a plunger 105 is held, against the action of a spring 107, to maintain contacts 108, 109 closed. When the pressure is cut off, the spring 107 causes the contacts 108, 109 to be separated, thereby lighting a warning lamp. When the valve 160 closes, its stem 110 moves into position to open a connection between the lines 96, 97, thereby allowing the hydraulic motor 83 to run freely, as it is driven through the gears 99, 98, on continued operation of the still effective motor 83a.

On seizure of the control valve 36a, a precisely similar action takes place. The member 23a collapses and the valve 160a closes, to cut off pressure from the valve 36a, to energize the associated warning lamp, and to connect together the lines 96a, 97a.

Interlocking plungers 111, 111a are provided between extensions 112, 112a of the tubes 51, 51a of the two collapsible members 23, 23a. These operate, as described in U. S. application Serial No. 164,759 when either of the members 23, 23a collapses, to lock the other against collapse.

The invention, in its application to duplicated hydraulic actuators, is of utility only when applied to actuators directly coupled to the output member, e. g. jacks in tandem, as shown in Fig. 2, jacks in parallel and both directly coupled to the output member and motors mounted in tandem on or directly geared to a common output shaft. In the case of actuators differentially coupled to the output member, i. e. jacks in parallel coupled to the output member through a differential link as described in U. S. application Serial No. 164,654, or motors coupled to the output member through a differential gearing, a failed and short-circuited actuator can be driven in reverse by the still operative actuator, and it is necessary to provide a pressure responsive lock which operates in case of failure, e. g. as described in U. S. application Serial No. 164,654, to lock the failed actuator.

What we claim as our invention and desire to secure by Letters Patent is:

1. The combination with a hydraulic actuator having an inlet for liquid under pressure and an exhaust outlet, of a manually operable input member and an output member adapted to be actuated by the actuator, said actuator comprising a control valve movable in opposite directions by said input member to cause liquid to flow through said actuator in alternative paths from said inlet to said outlet and thereby to cause said actuator to move said output member in a direction and to an extent determined by the movement imparted to said input member, a collapsible member linked to the input member and arranged to collapse, in the event of seizure of said control valve and consequent abnormal application of manual force to said input member, a conduit for permitting of free circulation of liquid within the actuator, a valve normally closing said conduit, and means controlled by the collapsible

member and operative on collapse thereof to cause automatic opening of said valve.

2. The combination with a hydraulic actuator having an inlet for liquid under pressure and an exhaust outlet, of a manually operable input member and an output member adapted to be actuated by the actuator, said actuator comprising a control valve movable in opposite directions by said input member to cause liquid to flow through said actuator in alternative paths from said inlet to said outlet and thereby to cause said actuator to move said output member in a direction and to an extent determined by the movement imparted to said input member, a collapsible member linked to the input member and arranged to collapse, in the event of seizure of said control valve and consequent abnormal application of manual force to said input member, a conduit for permitting of free circulation of liquid within the actuator, a valve subject to hydraulic pressure within the actuator, and a catch controlled by the actuator for normally holding said valve closed, said catch being disabled on collapse of the collapsible member to permit said hydraulic pressure to move said valve to open said conduit.

3. The combination with a hydraulic actuator having an inlet for liquid under pressure and an exhaust outlet, of a manually operable input member and an output member adapted to be actuated by the actuator, said actuator comprising a control valve movable in opposite directions by said input member to cause liquid to flow through said actuator in alternative paths from said inlet to said outlet and thereby to cause said actuator to move said output member in a direction and to an extent determined by the movement imparted to said input member, a collapsible member linked to the input member and arranged to collapse, in the event of seizure of said control valve and consequent abnormal application of manual force to said input member, a conduit for permitting of free circulation of liquid within the actuator, a valve for closing said conduit, a catch controlled by the collapsible member for normally maintaining the valve in closed position, and a spring urging the valve to position to open said conduit, said catch being disabled, on collapse of said collapsible member, to permit said spring to open said valve.

4. In combination, a pair of hydraulic actuators each having a pressure inlet and an exhaust outlet, an input member common to the two actuators, and a common output member adapted to be actuated by the two actuators, each actuator comprising a control valve movable in opposite directions by said input member to cause liquid to flow through said actuator in alternative paths from said inlet to said outlet and thereby to cause said actuator to move said output member in a direction and to an extent determined by the movement imparted to said input member, a collapsible member linked to the input member and arranged to collapse, in the event of seizure of said control valve and consequent abnormal application of manual

force to said input member, a conduit for permitting of free circulation of liquid within the actuator, a valve normally closing said conduit, and means controlled by the collapsible member and operative on collapse thereof to cause automatic opening of said valve, said actuators being directly coupled to said output member.

5. The combination with a hydraulic jack, comprising a servo member and a housing therefor, of a manually operable input member, an output member coupled to the jack, a pressure inlet, an exhaust outlet, a control valve coupled to the input member and movable in opposite directions from a neutral position to establish alternative connections between opposite ends of said housing and said inlet and outlet and thereby cause relative movement between said housing and servo member to move the output member in a direction and to an extent determined by the movement imparted to the input member, a collapsible member coupled to the input member and arranged to collapse, on seizure of said control valve, under application of manual force to the input member, a conduit for permitting liquid to flow freely between opposite ends of said housing, a normally closed valve in said conduit, and means controlled by said collapsible member for freeing said valve, on collapse of said collapsible member, for automatic movement to its open position.

6. The combination with a hydraulic motor, of a manually operable input member, an output member actuated by the motor, a pressure inlet, an exhaust outlet, a control valve movable by said input member in opposite directions from a neutral position to establish a flow of liquid through said motor from said inlet to said outlet in alternative directions according to the direction of movement of said control valve and thereby to cause said motor to move said output member in a direction and to an extent determined by the movement imparted to the input member, a collapsible member coupled to the input member and arranged to collapse, on seizure of said control valve, under application of manual force to the input member, a conduit for permitting liquid to circulate freely through said motor, a normally closed valve in said conduit, and means controlled by said collapsible member for freeing said valve, on collapse of said collapsible member, for automatic movement to its open position.

ROY WESTBURY.
